ELECTRIC FURNACE FOR THE MANUFACTURE OF CONDENSABLE PRODUCTS

Roger Emile Lambert, Paris, France; vested in
the Alien Property CustodianApplication January 9, 1942, Serial No. 426,212
In France June 24, 1940

5 Claims. (Cl. 13--8)

The object of the present invention is a revolving or oscillating furnace, functioning in a reduced atmosphere, for the manufacture of condensable products and especially of metals such as magnesium, by means of chemical reactions, capable of giving rise to an evolution of vapors which can be separated by condensation.

The furnace according to the invention comprises essentially a reaction chamber of a general cylindrical shape, the axis of which is horizontal, mounted so as to be able to revolve or oscillate around the said axis; one or several heating resistances or "resistors," consisting respectively of a rod of graphite or equivalent substance mounted in the axis of the reaction chamber or near to this axis, and supported at its ends by electrodes acting as supply mains, and a removable condenser provided with cooling means, for collecting and condensing the vapors evolved by the reaction.

According to one of the features of the invention, the condenser is composed of a metallic casing mounted so as to be removable, under a cover also removable and connected to the reaction chamber, the said cover bearing cooling means on its walls (a water tube for instance). This arrangement permits more particularly an easy substitution of the condenser during the treatment of the reacting substances, it being possible to separate the condenser properly speaking from the cover under which it is mounted in view of an ulterior treatment of the condensed product, such as the melting of this product. Moreover, the fact of putting simultaneously under a vacuum the cover and the condenser allows the latter to be built with thin sides which condition will ensure a good thermal conductivity.

The construction of the removable condenser, as it has been described above, is particularly advantageous when the condenser is placed axially at one of the ends of the reaction chamber of the furnace, the current being supplied to that end of the furnace through the cover which supports the condenser. It can however also be applied to a condenser disposed laterally in the charging door of the furnace.

In any case, the cooling apparatus disposed on the cover bearing the condenser can be multiple and provided with regulating means giving the possibility of fixing in advance the zones of the condenser where the deposit of the product which is to be condensed will take place.

According to another feature of the invention, the supply electrode supporting the resistor on the side opposite to the condenser, is advantageously connected to the casing of the furnace by an undulated and supple membrane, so as to permit the free expansion of the resistor while ensuring the tight closing of the furnace, ad-

justable springs being provided to counter-balance the action of the atmospheric pressure on the supple membrane, and therefore on the resistor.

5 An embodiment of the furnace, object of the invention, is represented as an example not inclusive of all cases on the appended drawings. On these drawings:

Fig. 1 is a diagram of an axial, longitudinal 10 section of the furnace;

Fig. 2 is a side view on a larger scale of the cover bearing the removable condenser;

Fig. 3 is an axial longitudinal section, also on 15 a larger scale, of the compensated supple joint bearing the supply electrode on the side opposite to the condenser.

As represented in this embodiment, the furnace according to the invention is composed of a cylindrical reaction chamber 1, the axis of which 20 is disposed horizontally, and the casing 1a of which is made of refractory materials. The cylindrical casing of this chamber is provided with a charging and discharging orifice 2 closed by a door consisting of a stopper 3 mounted on a plate 4 held fast by nuts 5 which can be rapidly loosened. This plate 4 ensures at the same time the tightening of a plastic joint 6 against a projecting frame 7 provided around the orifice 2.

30 The chamber 1 is provided externally with tracks 8a, 8b, which rest on rollers 9a, 9b, and which permit giving it a revolving or oscillating movement around its axis.

At its ends, the reaction chamber 1 has two 35 axial openings 10a, 10b, in which are disposed two blocks 11a, 11b, made of graphite or any other similar material which serve as supports for a resistor 12 also made of graphite and mounted in the axis of the furnace. Instead of one resistor only, several could be provided, mounted near to the axis of the furnace. The blocks 11a, 11b act as an integral part of two hollow metallic electrodes 13a, 13b provided at their free ends with metallic discs 14a, 14b which dip 40 into baths of liquid metal contained in tanks 15a, 15b to which feeders 16a, 16b are connected, the said feeders being also connected to the supply mains of a source of electrical energy (not shown). Pipes 17a, 17b, penetrate into the electrodes 13a, 13b, ensuring an internal circulation of cooling water.

45 A removable condenser 18 having a thin spherical metallic casing is set at one of the ends of the furnace. This condenser is set in the axis of the furnace and has an opening 19 which communicates through the opening 10b with the interior of the reaction chamber. It is supported and maintained against the end of the furnace—provided with a hollow 1b of appropriate shape in order to receive it—by a metallic

cover 20 provided with brackets 21 and fastening tightly by means of clamps 22 onto the front side of the furnace. A plastic lining 23, for example of rubber, ensures that the joint is tight. The cover supports moreover the corresponding hollow electrode 13b enclosed in an insulating sheath 24 and receives a tube 25 connected to an apparatus producing a vacuum (not represented), this tube being protected by deflectors 26 conveniently disposed in the condenser. Water circulation tubes 27-28 provided with regulating taps and intended for the refrigeration of the condenser are mounted on the side walls of the cover.

The opening 10a of the furnace, opposite to the condenser 18, is closed by a cover 29 (Fig. 3) fastened to the corresponding wall of the furnace. The cover 29 is prolonged externally by an undulated and supple membrane 30 which is soldered to it at one of its ends, the other end of it being soldered to a sleeve 31 fastened in a rigid and tight way onto the supply electrode 13a. The joint thus constituted ensures a tight closing of the furnace, while still permitting the free dilatation of the resistor 12, the electrode 13a being able to move axially owing to the possibility of extension of the undulated membrane 30 to which it is connected. Compressed springs 32 are provided to exert on the electrode 13a, an action contrary to that of the atmospheric pressure to compensate the action of the atmospheric pressure on the resistor 12 when the vacuum is obtained in the reaction chamber 1, and thus avoid the deformation of the said resistor which might result. These springs bear at one end on stops 33 provided on rods 34 disposed around the electrode 13a and acting as an integral part of the cover 29, and at the other end on a disc 35 mounted freely on the sleeve 31 but which props up against a fly wheel 36 screwed onto the said sleeve. The degree of compression of the springs 32 is modified by screwing the fly wheel 36 more or less onto the sleeve 31 and it is thus possible to regulate their compensating action.

The furnace thus constituted works as follows, for instance when it is used for the manufacture of magnesium:

The removable condenser 19 is well fitted into the hollow 1b of the side of the furnace, in order to obtain a tight joint of the cover 20. Then, having charged in advance, or only after the mounting of the condenser, the substances to be treated which consist for instance of a mixture of oxides of oxygenated alkaline earth compounds more or less rich in magnesium, and of reducing agents such as silicides, ferro-silicon etc., the desired degree of vacuum is established in the reaction chamber and the electric current is made to pass through the resistor 12 and the whole furnace is set rotating. The vapors of magnesium which evolve from the mass in reaction flow through the opening 10b and are condensed in the interior of the condenser. When it is desired to remove the condenser, the atmospheric pressure is reestablished in the interior of the reaction chamber, the tightening clamps 22 are loosened, the cover 20 is removed from the furnace, which allows the removing of the condenser 19 in order to collect the condensed magnesium or proceed to a further treatment of it.

It is possible to determine at will the zones of the condenser in which the deposit of the product is to take place, by modifying the dis-

charge of the various refrigerators 27-28 during the reaction.

Of course, and as it has already been shown in what precedes, the invention is not limited in its embodiments to the devices represented on the appended drawings. It is possible to give to the condenser a shape other than spherical, and as has been said above, the ensemble cover-condenser, can be set in any other part of the furnace, for example against the charging orifice 2, in order to act as a tight closing for that orifice, instead of the door constituted by the stopper 3 and the plate 4.

What I claim is:

1. An electric furnace for the manufacture of condensable products, which comprises a furnace part of generally cylindrical shape and hollow within to provide a reaction chamber, said furnace part being disposed with its axis substantially horizontal, means supporting said furnace part and mounting it for rotative movement about said axis, electrode supporting means mounted axially at one end of said furnace part and in gas-tight relation therewith, an electrode in said electrode supporting means, a housing detachably mounted in gas-tight relationship and in an axial position at the other end of said furnace part, electrode holding means axially mounted on said casing, an electrode therein, and a removable condenser shell axially mounted within said casing, and in communication with said reaction chamber.

2. The structure claimed in claim 1 including means for exhausting said reaction chamber, said casing and said shell.

3. The structure claimed in claim 1 including means for exhausting said reaction chamber, said casing and said shell, said electrodes bearing between them a resistance heating member adapted to extend across said reaction chamber in a substantially axial position.

4. The structure claimed in claim 1 including means for exhausting said reaction chamber, said casing and said shell, said electrodes bearing between them a resistance heating member adapted to extend across said reaction chamber in a substantially axial position, said first mentioned electrode supporting means being mounted with respect to said furnace part in an axially movable manner, the gas-tight relationship being maintained by flexible metallic means permitting said axial movement, and means in connection with said electrode supporting means to neutralize in part at least the inward thrust of the atmosphere on said electrode supporting means when said apparatus is exhausted.

5. The structure claimed in claim 1 including means for exhausting said reaction chamber, said casing and said shell, said electrodes bearing between them a resistance heating member adapted to extend across said reaction chamber in a substantially axial position, said first mentioned electrode supporting means being mounted with respect to said furnace part in an axially movable manner, the gas-tight relationship being maintained by flexible metallic means permitting said axial movement, means in connection with said electrode supporting means to neutralize in part at least the inward thrust of the atmosphere on said electrode supporting means when said apparatus is exhausted, and fluid cooling means in connection with said housing.

ROGER EMILE LAMBERT.
